UNITED STATES PATENT OFFICE.

BAPTISTE VAURS, OF PARIS, FRANCE.

MACHINE FOR MAKING BOLTS, PINS, SPINDLES, VALVES, AND THE LIKE.

Application filed November 6, 1924, Serial No. 748,086, and in Great Britain November 16, 1923.

This invention relates to a forging and stamping machine, chiefly for making bolts in three stages but also applicable for making pins, spindles, valves and the like. To this end, the machine may be provided successively with three different dies, but a generally preferred arrangement is three machines side by side each provided with the dies required for one stage respectively.

10 Whatever the article to be manufactured, the machine according to the invention essentially comprises a press on the stand of which a block is adapted to move and be locked in its operative position by means of detents. Operating means are provided for simultaneously actuating the said detents and a slide supporting the rod or blank from which the article, for example a bolt, is made. The bolt head is formed at one end 20 of the said blank, the said end being forged and stamped by the dies. The elements liable to become unduly heated are cooled by air. The block is guided on adjustable slideways so as to enable the attendant to 25 take up the slack.

The numerous advantages of the machine according to the present invention may be readily grasped from the following description. The machine is suitable for manufacturing the above-mentioned articles with precision and on a large scale, the waste of metal being very small.

A constructional example of the machine according to the invention and intended for 35 making bolts, from which its general application will be readily understood, is illustrated in the accompanying drawings in which—

Figure 1 is a diagrammatic view, 40 Figure 2 is a cross-section through the sliding block of the machine, ready to perform the work done in the first stage.

Figure 3 shows the sliding block ready for the second stage, in longitudinal section 45 partly through a vertical plane coincident with the axis of the machine and partly through a vertical plane coincident with axis of the operating shaft.

Figure 4 is a cross-section through the 50 sliding block ready for the third stage.

Figures 5 and 6 illustrate an arrangement whereby the machine may be worked automatically.

Referring to Figures 1 to 4, the blank carrier or block 2 is supported on the bed plate

1 suitably disposed on the frame 3 of the press which is operated in the usual way by a shaft 4 rotated by a pulley 5 and suitably connected by a link or connecting rod 7 to the hammer or ram member 8. The said 60 hammer is guided between the two uprights of the press and carries the upper die 9. The dies used in the first and second stages have a suitable cavity 10 while the die for the third stage has a hole 11 of hexagonal 65 contour. The die 9 is always held in position by a ring 12 threaded on the end of a head 13 mounted in the hammer 8 in any desired manner, provided that it may be easily removed and replaced. Cooling air 70 is supplied to the said head through a screw-threaded duct 14, the said air passing along a tube 15 and coming into contact with the die 9, after which it leaves the head through ducts 16. The lubricating oil 75 required for the third stage is supplied through a duct 17.

The lower portion or foot of the block 2 is cut in dove-tail fashion and slides between two guides 18 bearing against two 80 parallel holding-down members 19 bolted to the bed plate 1. The inner faces of the guides 18 converge towards the back of the machine so that any slack due to wear may be taken up by moving the said guides 85 longitudinally in a forward direction. The end movements of the block 2 are limited by a stationary stop 20 constituted by a plate screwed to the bed plate 1, and by an adjustable stop 21 constituted by a bolt 90 screwed into a support 22 secured to the said bed plate.

The block 2 has three cylindrical vertical bores disposed along its longitudinal axis, each bore being adapted to receive a slide. 95 The two outer or end slides 23 are each provided at one end with a movable detent 24, their other ends each having a spring 25 abutting on a cover 26 closing the upper end of the bore. The detents 24 are adapted 100 to snap into engagement with suitable sockets 27 sunk in the bed plate 1 which is also provided with a bar 28 made of hard metal with which the detents are in frictional contact while the block 2 is moving. The said block is locked in position by the detent and slide arrangement just described and is released by means of a wheel 29 mounted on a shaft 30 horizontally disposed in the 105 said block and carrying a pinion 31 en-

gaging a rack 32 cut laterally on each of the slides 23.

The central bore also contains a suitably dimensioned slide 33 provided with a rack 5 engaging with the pinion 31, and also provided with a groove 34 into which projects the end of a screw 35. A vertical hole 36 drilled in the said slide is adapted to receive the rod or blank and may be varied 10 in length by a screw 60 in accordance with the length of the bolt to be made. The upper portion of the central bore is enlarged and is adapted to receive the lower die which is pierced by a hole. A die 37 is 15 provided for the two first stages and is arranged in a holder 38 supported on the block 2. The said die and holder are held in position by a ring 39 screwed in a ring 40 secured to the block by bolts 41 (Figure 20 3). The die for the third stage is held in a similar manner in a holder 38, but is moreover provided with a punch 42 which surrounds the assemblage and on which the bolt head rests when it is given its hexagonal shape. The block 2 has a duct 43 (Figure 25 2) through which compressed air is led to the die for cooling the latter. Oil ducts 44 are also provided for lubricating the guides 18.

30 The machine works as follows: The block being in contact with the stop 20, the suitably heated rod or blank is placed in the die 37 of the machine held in readiness for the first stage. The block 2 is now moved 35 on the bed plate 1 until the detents 24 engage the sockets 27, when the elements are centered in their working position. The press is now operated by means of a suitable 40 pedal and the hammer causes the end of the blank to be pressed into shape in the dies. The wheel 29 is now rotated in the correct direction for raising the three slides 23 and 33 and releasing the block 2 which may be brought back to its initial position. The 45 blank is raised, easily removed and brought to the second machine, in which the operation is repeated. The unfinished bolt is now brought to the third machine in which the bolt head is punched into its final shape.

50 The machine or machines need not be manually operated. A mechanical operating device is illustrated in Figures 5 and 6, in which a bevel wheel 45 keyed to the driving shaft 4 meshes with another bevel 55 wheel 46 carried on a vertical shaft 47 suitably disposed on the frame 3 of the press. A shaft 49 lying under the bed plate 1 in the vertical plane of the shaft 30 of the hand wheel, is rotated by the shaft 47 through an 60 intermediate shaft 48. The block 2 has a lateral finger 50 adapted to contact with the periphery of a suitably shaped cam 51 keyed to the shaft 48 and adapted to move the block 2 which is returned by a counter- 65 weight 52 connected to the said block by

a cord or cable 53 passing over a pulley 54. The means locking the said block in position are released (when the block is to be moved) by means of a toothed sector 55 keyed to the driven shaft 49 and meshing 70 with a suitably toothed portion of the shaft 30 for the purpose of raising the slides 23 and 33 through the medium of the pinion 31. The block 2 is to leave its loading position at the attendant's will only; a bolt 56 75 is provided for this purpose.

The machine as described so far does not totally eject the finished article which is only raised when the slide 33 rises. Total ejection may be attained by providing the 80 bed plate 1 with a hole 57 in which a suitably held and guided ejector 58 is adapted to move. This ejector is jerkily raised by a tappet 59 secured to the shaft 49 so that the said ejector is operated when the slide 33 is vertically above it. Of course the various elements of the above-described mechanism are positioned relatively to each other so that they are moved in their correct and pre-determined order.

The machine according to this invention may be modified in its details without departing from the invention. For example in the automatically working arrangement, the transmission of power from the driving 90 to the driven shaft may be effected by any suitable means. In a similar manner, the block may be returned by a spring, a rack or a link.

I claim:

1. A press, comprising a recessed bed plate; a block slidable thereon and provided with a vertical bore; a slidable work-receiving member in the bore; a plurality of movable detents carried by said block for engagement in the recesses in the bed plate; a vertically-movable hammer above the block; a pair of coacting dies, one mounted in the hammer and the other in the upper end of said bore; and an actuating device 100 common to the detents and the work-receiving member for raising them simultaneously.

2. A press, comprising a bed plate having a plurality of recesses; a block slidable on said plate and having a plurality of vertical bores including a detent-receiving bore individual to each recess and a work-receiving bore; a spring-loaded detent slidable vertically in each first-named bore and adapted for engagement in said recesses; a work-receiving member slidable vertically in the second-named bore; a vertically-movable hammer above the block; a pair of co-acting dies, one mounted in the hammer and the other in the upper end of said second-named bore; and an actuating device common to the detents and the work-receiving member for raising them simultaneously.

3. A press, according to claim 2, in which each detent is carried by a sleeve that fits 120

slidably in the respective bore, each such sleeve and the work-receiving member being provided with a vertical series of rack teeth; and in which the common actuating device embodies a pinion engaging all said sets of teeth, and means for rotating such pinion.

4. A press, comprising a recessed bed plate; a block slidable thereon and provided with a vertical bore; guides adjustably attached to the bed plate and having converging internal wear-compensating faces for engaging the block; a slideable work-receiving member in the bore of said block; a plurality of movable detents carried by said block for engagement in the recesses in the bed plate; a vertically-movable hammer above the block; a pair of coacting dies, one mounted in the hammer and the other in the upper end of said bore; and an actuating device common to the detents and the work-

receiving member for raising them simultaneously.

5. A press, comprising a recessed bed plate; a block slidable thereon and provided with a vertical bore; a slideable work-receiving member in said bore; a plurality of movable detents carried by the block for engagement in the recesses in the bed plate; a vertically-movable hammer above said block; a pair of coacting dies, one mounted in the hammer and the other in the upper end of said bore; an actuating device common to all the detents and the work-receiving member for operating them simultaneously, said device embodying a shaft; and automatic means connected with said shaft for shifting said block while the detents are released.

In testimony whereof I affix my signature.

BAPTISTE VAURS.
